UNITED STATES PATENT OFFICE.

AUGUST R. LUSCHKA AND JOSEPH FOLK, OF LAPORTE, INDIANA, ASSIGNEES TO U. S. SLICING MACHINE COMPANY, OF LAPORTE, INDIANA, A CORPORATION OF INDIANA.

SHARPENER FOR SLICING-MACHINES.

1,308,433.

Specification of Letters Patent.

Patented July 1, 1919.

Application filed March 23, 1918. Serial No. 224,216.

To all whom it may concern:

Be it known that we, AUGUST R. LUSCHKA and JOSEPH FOLK, citizens of the United States, residing at Laporte, in the county 5 of Laporte and State of Indiana, have invented certain new and useful Improvements in Sharpeners for Slicing-Machines, of which the following is a specification.

This invention relates to devices for sharpening the rotary knives of machines for slicing meat and other material, and has for its object the provision of a sharpener which shall be of improved construction and operation.

15 The invention is exemplified in the combination and arrangement of parts shown in the accompanying drawings, and described in the following specification, and it is more particularly pointed out in the appended 20 claims.

In the drawings,

Figure 1 is a side elevation of a sharpener showing one embodiment of the present invention.

25 Fig. 2 is a top plan view of the sharpener shown in Fig. 1.

Fig. 3 is a vertical sectional view on line 3—3 of Fig. 2.

30 Fig. 4 is a horizontal sectional view on line 4—4 of Fig. 1.

Fig. 5 is a horizontal sectional view on line 5—5 of Fig. 1.

The knives of slicing machines must be kept constantly sharp in order to perform 35 the best work, and since they are circular disks of considerable size, it is desirable to have a grinder so mounted upon the machine that the sharpening operation can be performed automatically. It is also desirable 40 that this grinder shall be so arranged that it cannot be moved into and out of engagement with the knife in such a manner that the edge of the knife will be injured. In the drawings, the numeral 10 45 designates a bracket secured to the framework 11 of the slicing machine, the bracket 10 carrying a post 12 which is held in adjusted position in the bracket by means of a set screw 13. The post 12 carries a circular disk 14 rigidly secured thereto which forms a table for supporting the main frame or bearing block 15 of the grinder. The block 15, as shown in Fig. 3, is vertically bored at 16 to receive the upper end of the 55 post 12 upon which the block may be slid

vertically and also swung laterally, the post 12 forming a pivot for the lateral movement. A detent 17 is fastened to the block 15 by screws 18 and carries at its lower end an inwardly bent finger 19 in position 60 to engage the under surface of the table 14 to limit the upward movement of the block 15 upon the post 12. A series of notches 20, 21 and 22 is formed in the periphery of the disk 14 and a projection 23 65 is inwardly struck from the detent 17 for engaging these notches to prevent rotation of the block 15 about the post 12 when the block is in its lowermost position. When the block 15 is raised to its uppermost position, the projection 23 will be withdrawn from the notches in the disk 14 and the block with its grinders may then be freely 70 swung about the post 12, as a pivot.

The upper end of the block 15 is bored 75 horizontally to form a bearing 24 in which a pair of collars 25 and 26 are mounted for longitudinal sliding movement. The collars 25 and 26 are in turn centrally bored to form bearings for a shaft 27 which has collars 28 and 29 at its opposite ends arranged to form shoulders against which the grinders 30 and 31 are respectively held by nuts 32 and 33, threaded onto the outer ends of the shaft. The collars 25 and 26 are re- 80 siliently forced outwardly against the inner ends of the collars 28 and 29 by a coil spring 34 surrounding the shaft 27 and having its ends arranged to bear against the inner faces of the collars 25 and 26. The grinders 30 and 31 may be provided with guards 85 35 and 36 if desired.

The bearing portion of the block 15 is slotted, as shown at 37 in Fig. 4 of the drawings, and a screw 38 is threaded into 90 the collar 25 and projects outwardly through the slot 37. The outer end of the screw 38 passes through an opening in the end of a link 39 which has its opposite end pivotally connected with a lever 40 by means 95 of a screw 41. The lever 40 is rigidly connected by a screw 42 with a pin 43 extending transversely through the block 15, as shown more clearly in Fig. 5, and the upper end of the lever is provided with a finger 100 piece 44 by means of which the lever may be rocked upon its pivotal support formed by the pin 43. A coil spring 45 surrounds the end of the pin 43 opposite the lever 40 and has one end connected with the pin 110

43 and the other rigidly held by the block 15 so that the spring normally tends to rotate the pin 43 and the lever 40 in a clockwise direction, as viewed in Fig. 1. A catch 5 bar 46 is pivotally mounted at 47 on the upper portion of the block 15 and is provided with notches 48 for engaging an overhanging projection 49 on the lever 40. A spring 50 forces the catch bar 46 upwardly 10 into engagement with the projection 49. A finger piece 51 is provided for pressing the catch bar downwardly against the spring 50 to release the lever from the notches 48.

As shown in Figs. 3 and 5, the openings 15 for the pin 43 and the post 12 are so formed that they partially intersect one another. The pin 43 is partially cut away to form a notch 52 so that the pin will free the post 12 when it is turned into a position to bring 20 the face of the notch in a vertical plane. The parts are so related that this occurs when the lever 40 is thrown to its extreme position, as shown in Fig. 1, by the spring 45. The post 12 is also cut away to provide 25 a peripheral notch 53 which lies adjacent the pin 43 when the block 15 is in its lowermost position. It is apparent that this notch will permit oscillation of the pin 43 in unison with the lever 40 when the grinder 30 is in its lowered position. When the grinder is in its uppermost position the pin 43 will be raised above the end of the post 12 so that the lever 40 may be operated to rotate the pin 43 while in this position also. A post 35 54 is connected with the upper portion of the block 15 and carries a knurled head 55 by means of which the block with its connected parts may be raised and lowered and swung about the post 12. The post 54 is preferably 40 bored centrally to provide an oil duct for lubricating the various parts of the grinder. A fragment of the knife to be sharpened is shown at 56 in Fig. 3 of the drawings.

Assuming that the parts are in the position 45 shown in Figs. 1, 3 and 4 of the drawings, the grinder 31 may be brought into engagement with the beveled portion of the knife 56 by moving the lever 40 to the left in these figures until it engages one or the 50 other of the notches 48 of the catch 46. This movement of the lever 40 will cause the collar 25 to bear against the end of the spring 34 and the pressure thus exerted will be resiliently transmitted to the collar 26 55 and so force the shaft 27 to the left, as seen in the figures in the drawings, to bring the grinder 34 into engagement with the slicing knife. The grinder is resiliently held in this position by the engagement of the notches 48 60 with the lever 40 while the knife 56 is rotated by the mechanism of the slicing machine to perform the grinding operation. This grinding operation will bring the knife to a sharp edge, but will leave a bur on the 65 side of the edge opposite the bevel. To re-

move the bur the grinder is raised and rotated to bring the disk 30 into engagement with the flat surface of the knife. It should be noted that the steps in the change of the position of the grinder must occur in proper sequence to prevent injury to the knife. If the grinder were raised while in contact with the knife, the spring 34 would force the disk across the edge of the knife when the disk is raised to a point where it clears 75 the knife. Such upward movement of the grinder is made impossible, however, by the fact that the pin 43 is rotated to bring a portion of the pin beneath the upper shoulder formed by the notch 53 during the time that 80 the lever 40 is in position to hold the grinder against the knife. Before the grinder can be raised, it is necessary to release the catch 46 and permit the lever 40 to return under the influence of the spring 45 to its inoperative position. This return movement of the lever 40 will carry the collar 25 and consequently the grinder disks into their retracted positions, as shown in the figures of the drawings. The grinder is now free to move 85 upwardly and after it has been raised to clear the edge of the knife 56, it may be swung about the post 12 to bring the disk 30 into position adjacent the knife. It should be noted that the swinging movement cannot take place until the grinders are raised high enough to clear the edge of the knife, because of the engagement of the struck-in portion 23 of the detent 17 with the notches in the disk 15. The grinder cannot again be lowered unless the projection 23 is brought into position to register with one of the notches in the periphery of the disk 15. These notches are so positioned that 90 when the projection 23 registers with any one of them, the disk 30 will be in a position to clear the knife 56 when the grinder is lowered. One position is provided in which the grinder 31 will be adjacent the knife 56, another in which the grinder 30 100 will be adjacent the knife 56, and a third in which the shaft 27 will be parallel with the plane of the knife and both grinders will be in a neutral position. When the grinder has been raised and rotated to bring the disk 30 adjacent to and above the knife 56, it may then be lowered to bring the disk opposite the upper edge of the knife. In the retracted position shown in Fig. 3 of the drawings, the disk 30 is farther from the axis of the 110 post 12 than is the disk 31 so that when the disk 30 is lowered, it will be outside of the edge of the knife 56, or to the left of the knife, as viewed in Fig. 3, and may be drawn inwardly to engage the flat face of the knife 115 by a movement of the lever 40 similar to that used for focusing the disk 31 outwardly into engagement with the beveled edge of the knife. The same resilient contact between the grinder and the knife will be pro- 120 125 130

duced as in the former case because the force is transmitted in each instance through the spring 34. It should be noted that if it were attempted to lower the grinder while the lever 40 is moved to bring the grinder into operating position, such lowering of the grinder would be prevented by engagement between the pin 43 and the upper end of the post 12. This prevents moving the grinder 10 downwardly into contact with the upper edge of the knife and thus marring the edge.

It will be apparent that a grinder is thus provided which may be operated to grind the beveled edge of the slicing knife and subsequently remove the bur formed by the grinding operation, the parts being so related that an exact sequence of movement must be carried out in bringing the grinder into and out of operating position. In this 20 way any movement which would cause marring of the edge of the slicing knife is automatically prevented.

We claim:

1. A sharpener for slicing machine knives comprising a spindle having grinders carried at the opposite ends thereof, means for shifting said spindle to bring either of said grinders into position adjacent the knife to be sharpened, a spring for resiliently holding said grinders in engagement with said knife, and a device for exerting pressure on said spring and for positively shifting said spindle to move said grinders out of engagement with said knife.

35 2. A slicing machine comprising a spindle having a grinder connected with each of the opposite ends thereof, means for shifting said spindle to bring either of said grinders into a position adjacent said knife, a spring 40 for holding said grinders against said knife, and means for positively moving said grinders away from said knife.

3. A sharpener for slicing machine knives comprising a grinder, means for resiliently moving said grinder into engagement with said knife, means for positively moving said grinder out of engagement with said knife, and mechanism for controlling the direction of movement of said grinder toward said 50 knife to prevent injury to the edge of said knife.

4. A sharpener for slicing machine knives comprising a grinder, a spring for resiliently pressing said grinder against a knife 55 to be sharpened, means for actuating said spring to cause engagement between said grinder and said knife and for positively moving said grinder out of engagement with said knife, and mechanism for controlling the direction of movement of said grinder toward and from said knife to prevent injurious contact between said grinder and the edge of said knife.

5. A sharpener for slicing machine knives 65 comprising a spindle, a grinder carried by

said spindle at each of the opposite ends thereof, a pair of collars surrounding said spindle, a spring interposed between said collars, means for supporting said collars for movement in the direction of the axis of said spindle, and means for shifting one of said collars to cause said spring to resiliently move one of said grinders into engagement with said knife when said collar is moved in one direction and for withdrawing 70 said grinder from engagement with said knife when said collar is moved in the opposite direction.

6. A sharpener for slicing machine knives comprising a spindle having a grinder carried by each of the opposite ends thereof, a pair of collars surrounding said spindle between said grinders, a spring interposed between said collars, means for supporting said collars for movement in the direction 80 of the axis of said spindle, means connected with one of said collars for shifting said collar in one direction to exert pressure on said spring for resiliently forcing one of said grinders into engagement with a knife 90 to be sharpened, a spring for moving said collar shifting means in an opposite direction to withdraw said grinder from engagement with said knife, means for shifting the position of said spindle to bring either of 95 said grinders into operative relation with said knife at the will of the operator, and mechanism for controlling the movements of said spindle and grinders to prevent said grinders from improperly contacting with 100 the edge of said knife in a manner to injure said edge.

7. A sharpener for slicing machines comprising a spindle, a grinder carried by said spindle, a support for said spindle, means 105 for raising and lowering said support and for swinging said support laterally about an upright axis, a platform on which said support rests when in its lowermost position, and a detent having projections thereon 110 for limiting the upward movement of said support and for coöperating with recesses in said platform to control the angular position of said support about its upright axis during vertical movement of said support. 115

8. In combination, a sharpener for a slicing machine knife comprising a spindle, grinders connected with opposite ends of said spindle, sleeves surrounding said spindle and forming bearings therefor, a coil 120 spring surrounding said spindle between said sleeves and having its opposite ends arranged to bear against the inner faces of said sleeves, means for supporting said sleeves for movement in the direction of the axis of said spindle, an upright axis upon which said supporting means is mounted for vertical sliding movement and for horizontal pivotal movement, a lever connected with one of said sleeves 130

- and movable in one direction for exerting pressure upon said spring to force one of said grinders into resilient engagement with said knife and movable in an opposite direction to move said grinder out of engagement with said knife, means connected with said lever and movable therewith for controlling the vertical movement of said supporting means and the operation of said lever, a spring for normally holding said lever in position to hold said grinder out of engagement with said knife, a latch for holding said lever in position to hold said grinder in engagement with said knife, means for raising and lowering said spindle supporting means and for shifting said supporting means laterally to bring either of said grinders into operative relation with said knife, and means for preventing vertical movement of said spindle supporting means when said grinders are in position to be brought by said movement into injurious engagement with the edge of said knife.
- 15 9. The combination with a grinder for a slicing machine knife, of means for moving said grinder into and out of position adjacent to said knife, means for resiliently moving said grinder into contact with said knife and for moving said grinder positively and non-resiliently away from said knife, and mechanism for controlling the movement of said grinder to prevent injury to the edge of said knife.
- 20 10. A sharpener for a slicing machine knife comprising a shaft, a pair of grinders mounted in spaced relation on said shaft, means for shifting the axis of said shaft to bring said grinders alternatively into position adjacent said knife, means for shifting said shaft longitudinally of its axis to cause said grinders to engage said knife, and a spring arranged to cooperate with said last-mentioned shifting means to impart resilient movement to said shaft in one direction but permitting non-resilient movement to said shaft when said shifting means is moved in the opposite direction.
- 25 11. A sharpener for a slicing machine knife, comprising a shaft having a pair of grinders mounted thereon in spaced relation to one another, means for shifting the axis of said shaft to bring said grinders alternatively into position adjacent said knife, a collar slidably mounted on said shaft, means for shifting said collar in the direction of the axis of said shaft, a spring surrounding said shaft and engaging said collar to impart resilient movement to said shaft in the direction of the axis thereof when said collar is shifted in one direction, and an abutment for engaging said collar to impart non-resilient movement to said shaft in the direction of the axis thereof when said collar is shifted in the opposite direction.
- 30 12. In testimony whereof we have signed our names to this specification on this 18th day of March, A. D. 1918.
- 35
